UNITED STATES PATENT OFFICE.

RICHARD GUBIN, OF VIENNA, AUSTRIA-HUNGARY.

APPARATUS FOR PRODUCING AND PREPARING FOILS.

1,188,068.

Specification of Letters Patent. Patented June 20, 1916.

Application filed January 30, 1913, Serial No. 745,052. Renewed December 27, 1915. Serial No. 68,923.

To all whom it may concern:

Be it known that I, RICHARD GUBIN, a subject of the Emperor of Austria-Hungary, residing at 4 Anschützgasse XIII, Vienna, Austria-Hungary, have invented new and useful Improvements in Apparatus for Producing and Preparing Foils, of which the following is a specification.

This invention relates to an apparatus for producing foils from bronze, metallic or colored powder or the like, and for preparing metal leaves by the application of binding or adhesive means (shellac or the like); the invention consists of movable smooth support means (drum, endless band, or the like), the surface of which is prepared during its movement as follows: It first takes up the binding or adhesive means in a suitable layer, the metallic or colored powder or the metallic leaves are then applied on top of this adhesive layer and the layer is then solidified by suitable treatment, for example by heating, or cooling, or drying, according to the adhesive material used. This layer is loosened from the movable support by means of a suitable scraper and finally rolled up or cut.

The surface of the movable support dips into or passes through a trough containing the binding or adhesive means such as for example shellac, gelatin, or the like. The metallic or colored powder is placed in a removable receptacle on the frame of the drum or band and may be applied in an advantageous manner by suitable means as rollers or the like. As movable means may be employed: a rotatable drum, or roller of stone, glass, porcelain, polished metal, an endless band of steel, or a strong paper tape. The binding or adhesive means may also be applied to the drum or band by a receptacle kept under pressure.

The drawings show for instance a plurality of devices in accordance with the invention.

Figures 1 and 2 are a side and a front elevation respectively of an apparatus in which a drum or roller is employed as movable support. Figs. 3, 4 and 5 show diagrammatically examples of the apparatus with a band or strip of steel or a paper tape respectively instead of the drum or roller, and with the receptacle for the adhesive material placed above the band.

In Figs. 1 and 2, 1 indicates the frame of

the apparatus, 2 the bearing for the revoluble axle 3 on which is fixed a drum or roller 4 with a smooth surface 5 polished or provided with a layer of glass. Below the rotatable drum 4 the trough 9 is situated which contains the adhesive material 8 and on which in bearings 6 a roller 7 is provided dipping on the one hand into the solution and touching on the other hand the surface of the drum so that the surface 65 of the drum uninterruptedly may take up the solution from the roller which is put into rotation by the rotatable drum. The solution dropping down from the drum may be guided back to the trough 9 by a channel 11.

10 is a removable receptacle for the powder of metal, color, velvet flock (for velvet foils), or the like, this receptacle being open and in contact with the surface of the drum, so that the powder is taken up by the adhesive surface of the rotating drum. The excess powder is removed from the drum by rollers 12.

Heating devices 13 are provided for drying or stiffening the layer 8 of adhesive material on the drum surface. Instead of heating there may be employed cooling devices when the adhesive material becomes stiffened by cooling.

14 is a scraping tool by which the whole layer or manufactured foil is taken away from the surface of the drum.

15 is an endless band, carrying the foil to rotating knives or shears 16, by which the foil is cut into small leaves. Instead of cutting the foil band into leaves it may be also rolled up.

After passing the heating or cooling devices the dried or stiffened layer may be sprayed or pass a suitable device with a solution to make the foil waterproof.

This apparatus may also be employed for preparing individual metal-leaves, which are beaten, or gold-leaves, by providing the same with a layer of an adhesive material or the like. For this purpose the receptacle 10 is closed and the roller 12 is removed. On the frame 19 a revoluble pulley, or roller 20 is mounted which contains the metal leaves either in a wound paper band or as a continuous band. This band is unwound from the rotating pulley 20 in the movement direction of the drum 4, whereby the metal leaves 21 pass a roller 25, adhere on

the adhesive layer 8 of the drum, and are carried with the drum while the paper band passes a roller 23 and is wound up on the roller or pulley 24.

5. The further treatment of the adhered leaves is the same as before described.

Fig. 3 shows the employment of an endless steel band 26 as movable support, passing through the trough 9 containing adhesive material. The end-run of this band is then arranged horizontally or in the same direction with the transport band 15.

In the same manner a paper tape 27 (Fig. 4) of a material proof against the adhesive material used (parchmentized paper or the like) may be employed, this paper tape being unwound from a pulley 28 guided by rollers and finally wound up on the rotating and driven pulley 29. When the whole 20 paper tape is unwound from the pulley 28 and wound up on the pulley 29, these pulleys must be replaced by others.

Instead of applying the adhesive material by the roller 7 (Figs. 1 and 2), or instead of 25 carrying the movable band through the trough with the adhesive material (Figs. 3 and 4) the adhesive material may be supplied by the pressure of air, vapor, or a screw 32 or the like in a receptacle 31 situated above the band (Fig. 5) and provided on the under side with a slot or opening 33.

The modifications as illustrated in Figs. 3 to 5 contain all devices for applying of powder, heating or cooling, scraping and 35 cutting as before described relating to the apparatus according to Figs. 1 and 2.

Having now described the invention, and in what manner it may be used and modified, what I claim is:

40. 1. In an apparatus for producing and preparing leaves or foils from metal, the combination of means for spreading an adhesive material in form of a film with means for guiding metal leaves in direction of rotation of said film and in contact therewith, means 45 for varying the temperature in order to solidify the film after the application of

leaves and means for removing the prepared leaves.

2. In an apparatus for producing and preparing leaves or foils from metal, a drum, a receptacle containing adhesive material, a roller dipping into said receptacle and adapted to spread said adhesive material in form of a film, a roller containing metallic leaves, another roller adapted to bring said metallic leaves into engagement with said drum and means for varying the temperature in order to solidify the film after the application of said leaves. 60

3. In an apparatus for producing and preparing leaves or foils from metal, a drum, a receptacle containing adhesive material, a roller dipping into said receptacle and adapted to spread said adhesive material in 65 form of a film, a roller containing metallic leaves, another roller adapted to bring said metallic leaves into engagement with said drum and means for varying the temperature in order to solidify the film after the 70 application of said leaves and means for removing the prepared leaves.

4. In an apparatus for producing and preparing leaves or foils from metal, a drum, a receptacle containing adhesive material, a roller dipping into said receptacle and adapted to spread the adhesive material in form of a film on the surface of said drum, a roller containing the metal leaves and a roller adapted to guide said leaves in direction of rotation of said drum and into engagement with the same, an additional roller for guiding paper-tape removed from said leaves, means for winding up the paper-tape, means for varying the temperature in order to solidify the film after the application of 80 said leaves and means for removing the prepared leaves. 85

In testimony whereof I affix my signature in presence of two witnesses.

RICHARD GUBIN
